UNITED STATES PATENT OFFICE.

FREDRICK C. FIELDING, OF COALINGA, CALIFORNIA, ASSIGNOR OF ONE-THIRD TO
EDWARD A. WEBB, OF COALINGA, CALIFORNIA.

ANCHOR.

Application filed March 14, 1923. Serial No. 625,146.

To all whom it may concern:

Be it known that I, FREDRICK C. FIELDING, a citizen of the United States, residing at Coalinga, in the county of Fresno and 5 State of California, have invented certain new and useful Improvements in an Anchor, of which the following is a specification.

This invention relates to improvements in anchors and has for its prime object to provide a novel and easy means of supporting a 10 telegraph pole, fence post, etc. in a vertical position.

A further object of my invention is to provide an anchoring means whereby said 15 anchor is formed with a beveled cutting edge so that the anchor may be easily and quickly driven into the ground.

A still further object of my invention is to provide an anchor that after being driven 20 into the ground will assume a position at right angles to the object being supported, so that it will be impossible to dislodge the anchor from the ground.

And a still further object of my invention 25 is to provide an anchoring device of the character indicated, which is simple in construction, durable, efficient for the purpose intended, and one that can be manufactured and placed on the market at a relatively 30 low cost.

These and like objects of the invention will be better understood as the description follows and as is specifically pointed out in the appended claim.

Referring to the accompanying drawing 35 which forms a part of this specification,

Figure 1 is a perspective view of my improved anchoring means.

Figure 2 is a plan view partly in section 40 of my improved anchor.

Figure 3 is a side elevation of same, and

Figure 4 is a side elevation of the rod, partly broken away, which is used for driving 45 my improved anchor into the ground.

Referring to the accompanying drawing in detail, like characters will be used to 50 designate like parts in the different views.

In the drawing, the numeral 1 indicates as a whole my improved anchor, which comprises a flat diamond shaped blade having 50 bevelled cutting edges 2 formed on the front ends of same. The upper face of the blade 1 is provided with an eye 3 that is secured thereto in any suitable manner, and connected to the eye 3 is a rod 4, that extends 55 beyond the surface of the ground and is formed with an eye 5 in the upper end of same, so that a cable 6 may be attached thereto at one end and the opposite end of the cable engaging a telegraph pole 7 in any 60 suitable manner so as to support the latter in a vertical position as is clearly indicated in Figure 1.

In order to force the anchor 1 into the ground, the heel of same is provided with 65 a recess 8 therein, for receiving the end of a rod 9.

It can be thus seen that when the anchor 1 is placed downwardly in the ground and pressure is applied to the head of the rod 9, 70 the anchor 1 by means of the beveled cutting blade 2 is forced downwardly into the ground and caused to assume the position indicated in Figure 1 when a strain is placed on the rod 4.

In order to prevent the anchor 1 from turning over, a lip 10 is formed on the underside of the anchor, which prevents the strain of the pole or post from pulling the anchor over.

In view of the foregoing description of my invention taken in connection with the accompanying drawing, it is thought that any further explanation as to the construction, operation, and objects of my invention 85 is unnecessary.

While I have shown and described the preferred form of my invention, I realize that various minor changes may be resorted to, without departing from the spirit and scope of the invention as claimed, and therefore, I do not wish to limit myself to the exact details of construction shown, nor to the combination and arrangement of parts.

What I claim as new and desire to secure by Letters Patent is:

An anchor structure comprising a plate having opposite side edges converging 5 towards each other from the intermediate portion of the plate toward the end thereof, the plate being pointed at one end and provided at its opposite end with a socket the axis of which is in alignment with the 10 median longitudinal dimension of the plate, the plate being provided at its under side with a lip disposed at an acute angle to the

plane of the plate and extending from the intermediate portion of the plate under the socket an eye carried by the plate and located upon the median longitudinal dimension thereof and at a point between the ends of the converging side edges of the pointed end of the plate and a rod having link connection with the eye. 15 20

In testimony whereof, I have affixed my signature.

FREDRICK C. FIELDING.
